(57) **CLAIM**

The ornamental design for a solar array, as shown and described.

DESCRIPTION

FIG. 1 is a perspective view of a solar array showing our new design in a first position;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof;

FIG. 8 is a perspective view, showing the solar array in a second position;

FIG. 9 is a top view thereof;

FIG. 10 is a bottom view thereof;

FIG. 11 is a front view thereof;

FIG. 12 is a rear view thereof;

FIG. 13 is a left side view thereof;

FIG. 14 is a right side view thereof;

FIG. 15 is a perspective view, showing the solar array in a third position;

FIG. 16 is a top view thereof;

FIG. 17 is a bottom view thereof;

FIG. 18 is a front view thereof;

FIG. 19 is a rear view thereof;

FIG. 20 is a left side view thereof;

FIG. 21 is a right side view thereof;

FIG. 22 is a perspective view, showing the solar array in a fourth position;

FIG. 23 is a top view thereof;

FIG. 24 is a bottom view thereof;

FIG. 25 is a front view thereof;

FIG. 26 is a rear view thereof; and,

FIG. 27 is a left side view thereof, the right side view being a mirror image.

The illustrated positions of the solar array of our design are understood to be exemplary of possible alternate positions.
